US0D1016392S

(12) **United States Design Patent** (10) **Patent No.:** **US D1,016,392 S**
(45) **Date of Patent:** **** Feb. 27, 2024**

(54) **SHAVING RAZOR CARTRIDGE**

(71) Applicant: **The Gillette Company LLC**, Boston, MA (US)

(72) Inventors: **Jack Anthony Washington**, Mendon, MA (US); **Ulises Hernando Bautista**, Boston, MA (US)

(73) Assignee: **The Gillette Company LLC**, Boston, MA (US)

(**) Term: **15 Years**

(21) Appl. No.: **29/752,045**

(22) Filed: **Sep. 24, 2020**

(51) LOC (14) Cl. **28-03**

(52) U.S. Cl.

USPC **D28/47**

(57) **CLAIM**

The ornamental design for a shaving razor cartridge, as shown and described.

DESCRIPTION

FIG. 1 is a top perspective view of a first embodiment of a shaving razor cartridge;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a back view thereof;

FIG. 8 is bottom perspective view thereof;

FIG. 9 is a top perspective view of a second embodiment of a shaving razor cartridge;

FIG. 10 is a top view thereof;

FIG. 11 is a bottom view thereof;

FIG. 12 is a right side view thereof;

FIG. 13 is a left side view thereof;

FIG. 14 is a front view thereof;

FIG. 15 is a back view thereof; and,

FIG. 16 is bottom perspective view thereof.

The broken lines shown illustrate portions of the cartridge and form no part of the claimed design.

1 Claim, 10 Drawing Sheets
